UNITED STATES PATENT OFFICE.

JOHN MC GUIRE, OF MILWAUKEE, WISCONSIN.

WATER-CLOSET.

SPECIFICATION forming part of Letters Patent No. 245,193, dated August 2, 1881.

Application filed May 16, 1881. (No model.)

To all whom it may concern:

Be it known that I, JOHN MC GUIRE, of Milwaukee, in the county of Milwaukee, and in the State of Wisconsin, have invented certain new and useful Improvements in Water-Closets; and I do hereby declare that the following is a full, clear, and exact description thereof.

My invention relates to water-closets, and will be fully described hereinafter.

The drawing is a central vertical section of a water-closet embodying my invention, and in which—

A is the seat. B is the bowl. C is the pan, hinged, as usual, to a basin, D, which I have improved as follows: I cast or otherwise provide it with a chamber, J, into which I depend from the rim of the bowl, and just beneath the drip-opening H, a cage, F, having an opening, b, in its bottom, and in through opening b, I force a rubber ball, G. On the side of the basin D, opposite the chamber J, I provide said basin with an outlet-pipe, L, leading to a chimney or any other outlet in which there is a draft, so that there will always be a circulation of air through opening H into basin D and out through pipe L, keeping the space between the pan C and trap E free from foul air. This draft will also tend to draw the foul air from the bowl B after it has been used, for when the pan is dumped it will draw the gaseous contents down into the basin, to be carried out through pipe L.

I propose to provide the lift or seat of the closet with a suitable register to admit the air from the room to the opening H, and, as usual, this opening is just beneath the coupling I, so that any leakage from the coupling may fall into the basin.

Heretofore the drip-openings in water-closet basins have permitted the fluid which a stoppage in the sewer-pipe would cause to accumulate to escape and flow down upon the floor and thence to the ceiling below before it could be discovered. To remedy this I provide the ball G, which, when the basin has filled, will be carried up against opening H and completely close it, when the fluid, having no other outlet, will rise into the bowl at each dump of the pan, where it may be seen before it has done any damage. To prevent rust, I may face the opening H with brass.

I have shown the cage F as solid on all sides and having an opening at its bottom; but it may consist of depending U-bars or wire.

I am aware that I am not the first to ventilate water-closets by constructing them with an air-inlet on one side, beneath or at one side of the basin, and an air-outlet opposite thereto, whereby the basin may be kept clear of foul gases at all times by a continuous draft of air, and such I do not broadly claim.

I claim as my invention—

1. In a water-closet, the basin D, having drip-openings H, in combination with a ball 65 and cage, as set forth.

2. In a water-closet, the basin D, chamber J, cage F, air-inlet H, and valve controlling the same, in combination with the pipe L, substantially as shown and described.

In testimony that I claim the foregoing, I have hereunto set my hand this 25th day of April, 1881.

JOHN MC GUIRE.
